OR D 7,255

DESIGN FOR CARPET.

Design No. 7,255, dated March 24, 1874

UNITED STATES PATENT OFFICE.

JAMES C. JOHNSTON, OF SCARBOROUGH, NEW YORK.

DESIGN FOR CARPET.

Specification forming part of Design No. 7,255, dated March 24, 1874; application filed February 23, 1874.
[Term of Patent 3½ years]

To all whom it may concern:

Be it known that I, JAMES C. JOHNSTON, of Scarborough, in the county of Westchester and State of New York, have invented a Design for Carpets, of which the following is a specification:

The nature of my invention is fully set forth in the accompanying photographic illustration, to which reference is made; and

What I claim as new, and desire to secure by Letters Patent, is—
The design for carpets, as shown.

JAMES C. JOHNSTON.
